Attorney.

UNITED STATES PATENT OFFICE.

GEORGE A. FREDENBURGH, OF PAWTUCKET, RHODE ISLAND.

TWISTING-HEAD.

SPECIFICATION forming part of Letters Patent No. 760,619, dated May 24, 1904.

Application filed January 21, 1904. Serial No. 190,055. (No model.)

To all whom it may concern:

Be it known that I, GEORGE A. FREDENBURGH, a citizen of the United States, residing at the city of Pawtucket, in the county of Providence and State of Rhode Island, have invented certain new and useful Improvements in Twisting-Heads for Thread-Dressing Machines, of which the following is a specification.

This invention relates to a twisting-head adapted for a thread-dressing machine, and has for its object to provide a device of simple construction and arrangement of parts, so that a large number of twisting-heads may be mounted on the frame of the machine and each operating independent of the other.

A further object of the invention is to provide means for the ready insertion of a thread to the twisting-head in case of breakage of the thread during the operation of the device.

My present invention relates to an improvement on the thread-dressing machine described and claimed in Letters Patent No. 702,786, issued to me June 17, 1902.

In the accompanying sheet of drawings, Figure 1 represents a top plan view of the twisting-head as in position upon the frame of a thread-dressing machine. Fig. 2 is a central longitudinal sectional view of the twisting-head, taken on line X X of Fig. 1, and also showing a yarn-guide for directing the thread from said twisting-head. Fig. 3 is a top plan view of a series of said twisting-heads as mounted on the machine-frame and driven by the main shaft thereon. Fig. 4 illustrates a needle as threaded and ready to be inserted in the twisting-head in case of breakage of the thread during the operation of the same. Fig. 5 shows the manner of inserting a thread in the twisting-head by said needle.

Like letters of reference indicate like parts in the different views of the drawings.

A represents a bracket which has one end fixedly secured to the machine-frame B by bolts *a* and its opposite or front end provided with a vertically-arranged circular opening *b*.

C represents the twisting-head proper in the form of a whirl *c*, having an integral concentric annular hub *c'* projecting from one

side of said whirl and adapted to fit loosely in the opening *b* of the bracket. This twisting-head C is retained in position upon the bracket A by a screw *d*, which enters a threaded opening formed in the front portion of the bracket, and said screw has its inner portion *d'* exposing a smooth circular surface to enter an annular recess *c''*, formed in the peripheral surface of the hub *c'* of the twisting-head, as seen in Fig. 2.

The bracket A is provided with another threaded opening to receive a thumb-screw *d''*, whose inner end also enters the recess *c''*, and said screw is adapted to impinge against the twisting-head and hold the same from rotation during the time of applying a thread to be twisted, in the manner shown in Fig. 5. This twisting-head is provided with an opening *c'*, which forms a passage for the thread which is to be twisted, said opening extending from a point at the axial center of the bottom of the hub, as at *c'*, to a point offset from the center at the top of the whirl, as at *c''*.

e is a band or cord connection from a groove *c'*, formed in the whirl *c* of the twisting-head, to a grooved whirl *f*, fixedly secured on the main or driving-shaft *g* of the machine. (See Fig. 3.)

A slot *h* is formed longitudinally in the bracket A, so that the same may be drawn forward in putting a tension upon the driving-band *e*, after which the bolts *a* are screwed up tight to hold the bracket in place upon the machine-frame.

i is a bar situated over the twisting-head extending longitudinally therewith, and said bar is movably mounted in the machine-frame B and held in position thereon by a set-screw *j*. This bar *i* has a thread-eye *i'* at its front end to direct the thread to the brush-cylinder and ironers (not shown) next above on the machine.

The bar *i* is so adjusted on the machine-frame that its thread-eye *i'* is brought centrally with the axis of the twisting-head C.

The thread (designated by reference-letter *t*) comes up from the sizing-box (not shown) situated at the base of the machine, passes through the outwardly-directed opening or thread-passage *c'* of the twisting-head C, from

whence it passes to the eye z to be directed to the brush-cylinders and ironers. The thread in its upward movement bears at the points c^3 of the twisting-head and i' of the bar 5 z , and the twisting-head being driven at a high rate of speed by the driving-shaft causes the thread to roll between the said two points c^3 and i' of contact, and thus the proper twist is put upon the thread.

10 To afford quick means of applying a thread to this device in case of breakage of the thread during its feeding movement on the machine, I provide a needle k , having a knob k' at one end, which acts as a handle for the operator, 15 and its opposite end fork-shaped, as at k'' , to receive the parted end portion of the thread. The thumb-screw d^2 is then turned by the operator to make frictional contact upon and prevent rotation of the twisting-head, after 20 which the operator passes the needle through the opening or passage c^3 of the twisting-head and draws the free end of the thread therefrom, to be united or tied to the other free end of the thread from the winding-spool 25 above. After the ends of the thread are tied together the thumb-screw d^2 is unscrewed a trifle to allow rotation of the twisting-head by its constantly-moving band or cord.

By this construction and arrangement of 30 parts I form a device that is simple and compact, so that a large number of such devices may be mounted on a thread-dressing machine and each device operating independent of the other.

35 What I claim, and desire to secure by Letters Patent, is—

1. In a twisting-head mechanism for a thread-dressing machine, the combination of a bracket slidably secured on the machine-frame and provided with a vertically-arranged circular opening; a grooved whirl mounted 40 on said bracket, and having an integral concentric annular hub to loosely fit in the open-

ing of said bracket, and said second-named whirl and its hub provided with an opening 45 extending from a point at the axial center of the bottom of the hub to a point offset from the center at the top of the whirl; means to retain said second-named whirl in position on said bracket; a thumb-screw mounted in said 50 bracket and adapted to make frictional contact to prevent rotation of said second-named whirl; a band or cord connection from a driving-shaft of the machine to said whirl; and a bar movably mounted on the machine-frame 55 and provided with an eye arranged to direct the thread from the opening in said second-named whirl, substantially as shown and described.

2. In a twisting-head mechanism for a 60 thread-dressing machine, the combination of a bracket fixed on the machine-frame; a grooved whirl rotatably mounted on said bracket and provided with an annular recess and also provided with an opening forming a 65 thread-passage, which inclines outwardly from the axial center of said whirl; means to pass a thread through the opening of said whirl; a screw mounted in said bracket arranged to engage in the recess of said whirl in holding 70 the latter in place upon said bracket; a thumb-screw mounted in said bracket to impinge against and prevent rotation of said whirl; a band or cord connection from the driving-shaft of the machine to said whirl; and a bar 75 adjustably secured on the machine-frame and having a thread-guide arranged to direct the thread in a course centrally with the axial center of said whirl, substantially as described.

In testimony whereof I affix my signature in 80 the presence of two witnesses.

GEORGE A. FREDENBURGH.
